UNITED STATES PATENT OFFICE.

GEORGE A. CULLOM, OF ST. LOUIS, MISSOURI

CARTON-SEALING MACHINE.

1,118,475.

Specification of Letters Patent. Patented Nov. 24, 1914.

Application filed May 23, 1913. Serial No. 769,539.

To all whom it may concern:

Be it known that I, George A. Cullom, a citizen of the United States, and resident of St. Louis, Missouri, have invented certain new and useful Improvements in Carton-Sealing Machines, of which the following is a specification.

This invention relates to improvements in carton-sealing machines and reference is had 10 more particularly to that machine which is covered by my Patent No. 961,845, of June 21, 1910.

A prime object of this invention lies in the provision of new and improved devices 15 for gluing the cartons and for ejecting the empty cartons from the machine.

A further object lies in the provision of a machine of the character described in which the gluing devices are made adjustable, to the end that cartons of various sizes can be handled by one and the same machine; and a further important object lies in the provision of means for alternately raising and lowering members adapted to 25 retain the cover-flaps of cartons against the glue-distributing devices, so as to permit the free entrance of said flaps between said members and devices.

Referring to the accompanying drawings, 30 in which like numerals refer to like parts throughout the several views, Figure 1 is a side elevation of the complete machine; Fig. 2 a top plan view, scale enlarged, showing certain of the elements of Fig. 1; Fig. 3 a vertical sectional elevation taken along line A—B of Fig. 2; Fig. 4 a side elevation, partly in section, depicting in detail the rear portion of the machine; Figs. 5, 6, 7 and 8 detail views of certain important elements 35 hereinafter to be particularly described; Fig. 9 a perspective of the character of carton with which the machine is intended to deal; and Fig. 10 a diagrammatic view of the belt and pulley system employed herein.

Numeral 1 denotes the various portions of a frame-work serving to support the mechanism and in opposite ends thereof are journaled shafts 2—2^a carrying sprockets 3—3^a which serve to drive endless chains 4—4^a. Secured to said chains by means of cross- 50 rods 5 are a series of carton-carriers 6, between each of which is disposed a package-carrier 6^a. Said carton-carriers are best shown in Figs. 5, 6 and 8 and comprise a 55 hollow block 7 containing a plunger 8 having a lug 8^a projecting through slot 8^b and

an enlarged head 9 which is normally seated upon bar 5^a and connected with a helical spring 10. Referring to Fig. 5 it will be noted that a trip 11 affixed at the front of the machine is adapted to force head 9 of plunger 8 out of engagement with bar 5^a and that a curved arm 11^a is arranged so as to contact with lug 8^a of said plunger when the same has been brought to the upper extremity of slot 8^b through the action of spring 10.

The package-carriers are best shown in Figs. 4 and 7 and comprise a metal frame 12 (open above and on one side) and a lever 13 connected with a pivoted lug 14 which is adapted to move inward against the resistance of spring 15 when brought into contact with trip 16.

Near the front of the machine is disposed a folder-arm 17, the same being secured upon a rock-shaft 18 whose opposite extremity carries a lug 19 adapted to contact with strips 20 carried by cross-rods 5. While the automatic inward movement of arm 17 serves to depress end-flap 21 of the carton, stationary members 22 serve to depress end-flap 21^a thereof and also maintain side-flaps 23 in vertical position with the aid of guides 22^a.

Disposed adjacent members 22 is the gluing apparatus which comprises a pair of vertically disposed disks 24—24^a adjustably mounted upon a shaft 25 by means of set screws 26 and serving to close the inner end of glue-holders 27. As will be noted in Figs. 2 and 3 holders 27 are adjustably supported upon standards 28 by means of flanges 29 having elongated slots 30 through which are directed screws 31 and the flow of glue to disks 24—24^a is regulated by manipulation of screws 32 which are supported in metal straps 33 and bear directly against the outer end of holders 27. It will be appreciated that upon turning screws 32 in one direction they will force the inner edge of said holders so closely against disks 24—24^a as to prevent the flow of glue thereon and that on turning said screws in the opposite direction said holders will be gradually removed from contact with said disks so that the latter will take up the desired quantity of glue. Obviously the function of slots 30 is to permit holders 27 to be moved toward or away from each other to accord with the adjustment of disks 24—24^a.

Fig. 3 depicts certain important devices

by aid of which the side-flaps of the carton are pressed closely against the glue-carrying surface of disks 24-24^a and the same comprise a pair of conical rollers 34 secured to levers 35 which are pivoted at 36 and connected with arms 37. Between the upper extremity of arms 37 and the adjacent portion of the frame-work are disposed compression springs 38 which serve to force said arms toward said disks so that rollers 34 are normally retained in juxtaposition thereto and in order to momentarily lift said rollers away from said disks at regular intervals (to permit the free entrance of the side-flaps of the carton) lugs 39 projecting from levers 35 are disposed in the path of and adapted to be forced upward by trips 40 arranged at the base of carriers 6, 6^a.

Disposed between disks 24-24^a is a presser-foot 41 having an extension 41^a designed to hold down end-flaps 21-21^a of the carton and rearward of said disks are located the folders which serve to depress the side-flaps of the carton after the same have been glued. The folders last named (shown in Fig. 1) simply consist of a blade 42 affixed to the upper end of a rock-shaft 43 revolubly mounted in the frame-work 30 and carrying a lug 44 at its opposite end. Automatic operation of these folders is effected through the agency of trips 29 which contact with lugs 44 and thus serve to turn shafts 43 so that blades 42 are swung inwardly to depress the side-flaps of the carton. The cartons having been acted upon by blades 42 are next passed under a series of weighted rolls 46 mounted in an adjustable frame 46^a and the pressure of these rolls renders the sealing secure. The system of belts and pulleys employed herein is shown diagrammatically in Fig. 10. Therein it will be noted that shaft 2^a carries a pulley 47 which is connected with a motor (not shown) by means of belt 48. The opposite end of shaft 2^a carries another pulley 49 which is connected with pulley 50 by means of cross-belt 51, pulley 50 being mounted on shaft 52 whose opposite extremity carries a second pulley 53 which is connected with pulley 54 on shaft 55 by means of belt 56. Shaft 55 carries a second pulley 57 which is connected by belt 58 with pulley 59 whose movement serves to drive shaft 25. At the front of the machine is located a conveyer-belt 60 supported by pulleys 61-62 which are driven through the agency of a sheave 63 mounted on shaft 2 and connected with sheave 63^a by belt 64. A plunger 65, to which further reference shall be hereinafter made, is adapted to reciprocate across the path of belt 60 at regular intervals to deposit the filled cartons in carriers 6^a.

The operator standing at the front of the

machine spreads the empty cartons and places one thereof over each of carriers 6 as they are brought into vertical position through the movement of chains 4-4^a. The carton being thus started on its journey through the machine is first acted upon by arm 17 which serves to depress end-flap 21, while members 22 serve to depress end-flap 21^a and also maintain side-flaps 23 in vertical position with the aid of guides 22^a. Coincident with the entrance of flaps 23 between members 22 and guides 22^a lugs 39 (Fig. 3) come in contact with trips 40 and this results in momentarily lifting rollers 34 away from disks 24-24^a so that flaps 23 may freely enter between said disks and rollers. Trips 40 having passed beyond lugs 39 rollers 34 are instantly forced into substantially the position shown in Fig. 3 by the action of springs 38 and thus serve to retain flaps 23 in close engagement with the glue-carrying surface of said disks. While flaps 23 are passing through the operation just described end flaps 21-21^a have been brought beneath presser foot 41 and its extension 41^a, hence the sealing of the carton next follows in the depression of flaps 23 by folders 42 whose operation has already been described. The empty cartons having one end thus sealed now pass beneath rolls 46, pass thence over sprockets 3^a and are returned to the front of the machine. When the carriers 6 have passed about half-way around sprockets 3 trip 11 forces head 9 of plunger 8 out of engagement with bar 5^a, whereupon said plunger is subjected to the pull of spring 10 and thus projected beyond the upper surface of block 7 so as to expel the carton from the machine. Immediately after expulsion of the empty carton, lug 8^a contacts with and rides the inner edge of arm 11^a, which results in depressing plunger 8 until its head 9 is again locked in engagement with bar 5^a as shown in Fig. 8. The cartons having been filled with merchandise are next inserted (open end upward) in package-carriers 6^a and while this operation can be performed by the hand of the operator I prefer to employ conveyer-belt 60 and plunger 65. Plunger 65 and the means for its operation are substantially identical with the parts described in lines 64-82, page 2, and lines 8-13, page 3, of my prior patent hereinbefore mentioned, hence there appears no necessity for detailed description and illustration thereof in this application. The filled cartons being thus disposed (either by the operator or by plunger 65 co-operating with belt 60) in carriers 6^a their cover flaps are acted upon by the folding and sealing devices in the same manner as described with reference to the empty cartons and upon arriving at the rear end of the machine are ejected therefrom through the inward movement of lever 13

actuated by trip 16 as disclosed in Figs. 4 and 7.

What I claim as new and desire to secure by Letters-Patent is:—

- 5 1. A machine of the character described comprising carton-carriers, glue-holders, devices for distributing glue upon the cover-flaps of cartons supported by said carriers, members adapted to retain said flaps against said devices, and means for momentarily raising said members coincident with the entrance therebeneath of said flaps.
- 10 2. A machine of the character described comprising carton-carriers, glue-holders, separable devices for distributing glue upon the cover-flaps of cartons supported by said carriers, members adapted to retain said flaps against said devices, means for alternately raising and lowering said members, means for adjusting the distance between said devices, and means for adjusting said holders to accord with the adjustment of said devices.
- 15 3. A machine of the character described comprising carton-carriers, a plunger disposed within each thereof, devices adapted to retain said plungers in cocked position, a trip adapted to operate upon said devices to release said plungers, and mechanism adapted to cock said plungers after operation of said trip upon said devices, said carriers adapted to project within the cartons.
- 20 4. A machine of the character described comprising carton-carriers, a spring-actuated plunger disposed within each thereof, devices adapted to retain said plungers in cocked position, a trip adapted to operate upon said devices to release said plungers,
- 25 and mechanism adapted to cock said plungers after operation of said trip upon said devices, said carriers adapted to project within the cartons.
- 30 5. A machine of the character described comprising a conveyer, carton-carriers connected therewith, glue-holders, devices for distributing glue upon the cover-flaps of cartons supported by said carriers, rollers adapted to retain said flaps against said devices, pivoted levers supporting said rollers, lugs projecting from said levers, arms secured thereto, springs connected with said arms adapted to normally retain said rollers in juxtaposition to said devices, and trips carried by said conveyer adapted to lift said rollers against the resistance of said springs.
- 35 6. A machine of the character described comprising a conveyer, carton-carriers connected therewith, glue-holders, separable devices for distributing glue upon the cover-flaps of cartons supported by said carriers, means for adjusting the distance between said devices, means for adjusting said holders to accord with the adjustment of said devices; rollers adapted to retain said flaps against said devices, pivoted levers supporting said rollers, lugs projecting from said levers, arms secured thereto, springs connected with said arms adapted to normally retain said rollers in juxtaposition to said devices, and trips carried by said conveyer adapted to lift said rollers against the resistance of said springs.
